UNITED STATES PATENT OFFICE

HOMER R. WILCOX, OF QUAKER CITY, OHIO

PLASTERER'S CORNER-BEAD SETTER

Application filed January 5, 1928. Serial No. 244,607.

To neatly plaster a projecting vertical corner requires a very skilled workman, much time and great care. If a vertical projecting corner is not accurately plastered, especially those of chimney breasts, much trouble and disappointment are incurred in applying wall paper. To make the job of plastering easier there has been invented the now widely used "corner bead" consisting of a strip of sheet metal bent longitudinally in trough fashion perforated in the webs or wings and having a bead longitudinally at the corner. The "corner bead" is fitted at the corner of meeting walls to be plastered, the bead proper serving to fix in advance the limits of the plastering on the two walls. But this expedient gave rise to the new problem of preliminarily fixing the corner bead so that it might stand in an accurately vertical position. The use of plumb line was commonly resorted to but success in securing verticality is rare because the line necessarily stands away from the intended corner and the eye was ultimately relied on. The use of the plumb line also consumes much time. A number of devices have been proposed or patented for positioning the corner bead, hence the object of my invention is to provide an improved tool by means of which distortion or defects in the corner bead can be first detected and the bead discarded or straightened and then quickly and accurately set without a high degree of skill on the part of the setter.

The invention is embodied in the example herein shown and described, the features of novelty being finally claimed.

In the accompanying drawing—

Figure 1 is a view in rear elevation showing the invention applied to a corner bead. Fig. 2 is a plan view looking at the upper end thereof on a larger scale than appears in Fig. 1.

Fig. 3 is a rear view of fractions taken from near the middle of the holder showing details. Fig. 4 is a top plan view of the upper end of the device showing added to the gripping members means for latching said members in such relation to each other that the device may be used as a "straight edge." In the views 5, 5, designate the bodies of

the gripping members, said bodies being conveniently formed of long pieces of wood or metal having their forward edges mainly straight and flat and their rear portions formed for convenient manipulation. The flat portions of the forward edges can be each lined with a strip of brass as at 6, 6 if the gripping bodies be made of wood.

The forward edges of the gripper bodies are connected by a suitable number of hinges, 60 the leaves of which are indicated at 7, 7, and the pintle at 8. Around the pintle of each hinge is secured a coil spring 9, under tension, the extended ends of which press against the hinge leaves with a tendency to throw the body parts toward a common plane. The forward adjacent corners of the bodies are grooved or cut out, as best shown at 10, 10, Fig. 4, to fit on the beaded portion 11 of the corner bead and firmly grip them in practice as best shown in Fig. 2.

Each of the body portions, 5, 5, is provided near its middle with a "spirit level" glass 12 set in opening 13 and at a right angle to a line of the forward edge of the body so that when, as hereinafter described, both said edges are vertical the bubble of the glass will appear at the middle of the glass thus insuring that the corner bead held by the gripping member is in substantially vertical position. The fact that the bubble of one of the gripping bodies when holding a corner bead appears in the middle of its glass would not be evidence that both forward edges are in vertical position, hence these glasses cooperate with each other in indicating proper verticality for the corner bead contained in the instrument.

The character 14 designates a hook on the rear edge of one of the gripper bodies and 15 a headed pin on the other to be engaged by the hook to latch the gripper bodies in position as shown in Fig. 4 so that the tool can be used as a straight edge, its forward edge or edges serving in an obvious manner for this purpose. The pressure of the springs of the hinges being, as heretofore pointed out, to cause the bars to tend to go toward a common plane will aid in holding the latch in latching position until intentionally removed.

- In practice the corner bead will be placed in the instrument as shown in Figs. 1 and 2 and the inner angle of the bead supplied with a suitable coating of plaster of Paris promptly after which the corner bead, while still in the instrument, will be applied to the corner of the two walls to be plastered. In doing this due reference will be made by the workman to the two bubbles and proper adjustment of the instrument will be made by him to make sure that the corner bead is set in vertical position. The plaster of Paris upon hardening fixes the corner bead in position but such fixing can be aided by a nail or two at the top and bottom driven through holes in the corner bead. An advantage of the construction is that because the forward faces of the corner bead setter contact with the flanges as well as the intermediate bead any defects in the corner bead are detected, and is discarded or its defects rectified before application to the corner.
- The forms of the parts can be changed without departing from the gist of the invention as claimed.
- What I claim is:
1. An instrument for setting a plasterer's corner bead including a pair of substantially continuous bars having flat forward faces, said bars hinged together longitudinally at adjacent corners and adapted at said faces to grip the corner bead, including the flanges thereof throughout substantially their entire lengths, and spring means tending to hold said bars in corner bead gripping position.
  2. An instrument for setting a plasterer's corner bead including a pair of substantially continuous bars having flat forward inwardly beveled faces, said bars hinged together longitudinally at adjacent corners, said corners provided with grooves, and said bars adapted at said faces to grip the corner bead, including the flanges thereof throughout substantially their entire lengths, and spring means tending to hold said bars in corner bead gripping position.
  3. An instrument for setting a plasterer's corner bead including a pair of substantially continuous bars having flat forward inwardly beveled faces, said bars hinged together longitudinally at adjacent corners and adapted at said faces to grip the corner bead, including the flanges thereof throughout substantially their entire lengths, spring means tending to hold said bars in corner bead gripping position, and means for latching said bars with their forward faces in substantially the same plane.
  4. An instrument for setting a plasterer's corner bead including a pair of substantially continuous bars having flat forward faces, said bars hinged together longitudinally at adjacent corners and adapted at said faces to grip the corner bead, including the flanges thereof throughout substantially their en-
- tire lengths, spring means tending to hold said bars in corner bead gripping position, and means for latching said bars with their forward faces in substantially the same plane.
